Primary Examiner—Carmen H. Vales-Lado
Attorney, Agent, or Firm—Hoffman & Baron, LLP[57] **CLAIM**

The ornamental design for a chest of drawers, as shown and described.

DESCRIPTION

FIG. 1 is a top perspective view of a chest of drawers showing our new design;

FIG. 2 is a top plan view thereof;

FIG. 3 is a front elevation view thereof;

FIG. 4 is a side elevation view thereof, the opposite side being a mirror image thereof;

FIG. 5 is a top perspective view showing a chest of drawers according to an alternative embodiment of our new design;

FIG. 6 is a top plan view thereof;

FIG. 7 is a front elevation view thereof; and,

FIG. 8 is a side elevation view thereof, the opposite side being a mirror image thereof.

The bottom and rear views form no part of the claimed design.
